UNITED STATES PATENT OFFICE.

DANIEL HILLEMAN, JR., OF WELLSTON, MISSOURI.

COALING DEVICE.

1,097,434.

Specification of Letters Patent.

Patented May 19, 1914.

Application filed May 24, 1913. Serial No. 769,677.

To all whom it may concern:

Be it known that I, DANIEL HILLEMAN, Jr., a citizen of the United States, residing at Wellston, in the county of St. Louis and State of Missouri, have invented new and useful Improvements in Coaling Devices, of which the following is a specification.

The invention relates to an apparatus particularly designed for delivering coal to the tenders of traveling trains, the invention comprehending specifically a structure by which the coal is automatically delivered to the tender in the travel of the latter beneath the bins.

15 The main object of the present invention is the provision of a coal delivery apparatus including a series of bins arranged lengthwise of and above the track, each bin having a plurality of delivering sections adapted to be normally held in bottom forming position, a slide operated by the traveling train and normally locking the sections in position to complete the bottom of the bin, serving when operated to release said sections for the delivery of the coal by gravity.

20 The invention in its preferred form of details will be described in the following specification, reference being had particularly to the accompanying drawings, in which:—

25 Figure 1 is a plan of the improved coal delivering apparatus. Fig. 2 is a side elevation of the same with the dumping sections locked in position to form a bottom for the bin. Fig. 3 is a similar view with one of the locking slides in released position and the dumping sections in discharge position. Fig. 4 is a side elevation illustrating the relation of the coal delivery apparatus to the track, and showing means for operating the slide. Fig. 5 is a transverse section on the line 5—5 of Fig. 1. Fig. 6 is a longitudinal section on the line 6—6 of Fig. 1.

45 Referring particularly to the accompanying drawings, the improved delivery apparatus comprises a series of bins 1 including side and end walls 2 and 3, the bins being supported on a platform 4 arranged above the track 5 on a suitable framework 6.

The bins are arranged in longitudinal alinement and are each wholly independent, being preferably provided in series as shown, in order that a number of trains may

receive coal therefrom without the necessity of recharging the bin. The bottom of each bin is made up of a plurality, preferably two, dumping sections 7, each having a length approximately one-half the length of the bin and a width corresponding to the distance between the side walls of the bin. Each dumping section is pivotally mounted between side walls of the bin on a shaft 8, said shaft being secured to the section adjacent one end thereof, as shown. The shafts are preferably arranged adjacent similar ends of the dumping sections, that is the shaft of one dumping section will be secured thereto adjacent the end wall 3 of the bin while the shaft of the remaining dumping section will be secured thereto adjacent the center of the bin. By this construction the dumping sections tilt in the same direction in operation and therefore avoid the possibility of binding under the load. The shorter end of each dumping section is provided with a weight 9 serving to counterbalance the longer end of the section, so that when free to operate, the sections resume a horizontal or bottom forming position. The ends of the shafts 8 project beyond the side wall 2 of the bin, and are provided with locking members 10 rigidly secured to the shaft. Said members are of rectangular form having their major length corresponding and in alinement with the dumping section, and are arranged on the shaft so that they are in spaced relation from the side wall of the bin.

30 To the side wall of the bin in alinement with the locking members are fixed trackways 11 which trackways include guiding sections 12 secured to the sides 2 by reduced web portions, the guiding sections corresponding in width and height to the similar dimensions of the locking members.

A slide is arranged for coöperation with the trackways including a body 13 formed with a longitudinally extending channel 14 of a size to receive and coöperate with the trackways 11, the entrance to said channel through the inner side of the slide snugly fitting the web of the track way to prevent separation of the slide and trackway. The slide is also preferably provided with anti-friction rollers 15 which bear upon appropriate portions of the track in the movement of the slide, whereby to insure easy

movement and avoid undue friction. As the slide and channel are of a size and shift to coöperate with the trackways, it will obviously so coöperate with the locking members 10 when the latter are alined with the trackway. The slide is of a length exceeding the distance between the proximate ends of the trackways 11, so that the slide is always in coöperation with one or the other trackway. Depending from the slide at each end is a standard 16, which is preferably braced from the body by a brace 17.

The coal car is provided with hand operated lever 18 pivoted on the side thereof and connected to a trip lug 19 mounted in a recess 20 on the inner side of the car, the operation of the lever serving to project the lug above the car and into the path of the standard 16 of the slide, or to withdraw the lug beyond the possibility of coöperation with the standard.

In use, the slide bar is moved longitudinally of the trackways until it embraces both of the locking members 10 of the dumping section and by reason of the formation of said members, said slide will hold the dumping sections against movement toward dumping position. As the train approaches, which is to receive a load of coal, the lever 18 thereon is operated to project the trip 19 above the car. As the train advances said trip will engage one of the standards 16 and in the forward travel of the train move the slide lengthwise the trackway and free the locking members 10. The dumping sections, by reason of the load sustained, will immediately move to dumping position and discharge coal into the car, it being understood that the parts are so proportioned that the car moves beneath the dumping sections as the latter are released.

By providing a series of bins lengthwise of the track it is obvious that a number of trains can receive a load of coal without the necessity of continually recharging a particular bin and furthermore I contemplate any single track structure and arrangement of alternate bins so that they may be operated by trains traveling in opposite directions.

The various parts of the structure are to be constructed of substantial material which will stand the usage to which such devices are ordinarily put, and when so constructed will automatically deliver to a traveling train a load of coal from a particular bin without the necessity of stopping the train or other action by the crew except the adjustment of the lug 19. Any means may be provided for restoring the slide to locking position, such for example, as a cable or rod, it being understood that the dumping sections automatically return to normal position after having discharged their load, by virtue of which the locking members 10 are

automatically positioned to receive the slide when it is returned to set or operative position.

What is claimed is:—

1. A coal delivery apparatus including a bin arranged above the track, a dumping section forming a bottom for the bin, a locking member carried by the section, a track secured to the bin, and a slide coöperating with the track and engaging the locking member to hold the sections in bottom forming relation. 70

2. A coal delivery apparatus including a bin arranged above the track, a dumping section forming a bottom for the bin, a locking member carried by the section, a track secured to the bin, and a slide coöperating with the track and engaging the locking member to hold the sections in bottom forming relation, said locking member having a 75 sectional formation corresponding to that of the track in one direction. 80

3. A coal delivery apparatus including a bin arranged above the track, a dumping section forming a bottom for the bin, a locking member carried by the section, a track secured to the bin, and a slide coöperating with the track and engaging the locking member to hold the sections in bottom forming relation, said locking member having a 85 sectional formation corresponding to that of the track in one direction, and having a length exceeding the vertical dimension of the track in the other direction. 90

4. A coal delivery apparatus comprising a bin supported above the track, a plurality of dumping sections forming the bottom of the bin, each of said sections being pivotally mounted and adjusted to normally maintain their bottom closing relation in the absence 100 of material in the bin, a track secured on the outer side of the bin and interrupted throughout approximately the length of the dumping sections, a locking member carried by and movable with these sections, and a 105 slide coöperating with the track and set locking members to maintain said members and sections in relatively fixed positions with relation to the bin. 110

5. A coal delivery apparatus comprising 115 a bin supported above the track, a plurality of dumping sections forming the bottom of the bin, each of said sections being pivotally mounted and adjusted to normally maintain their bottom closing relation in the absence 120 of material in the bin, a track secured on the outer side of the bin and interrupted throughout approximately the length of the dumping sections, a locking member carried by and movable with these sections, a slide 125 coöperating with the track and set locking members to maintain said members and sections in relatively fixed positions with relation to the bin, said slide comprising a hollow body engaging the track and friction 130

rollers mounted within the body and bearing on the track.

6. A coal delivery apparatus comprising a bin supported above the track, a plurality of dumping sections forming the bottom of the bin, each of said sections being pivotally mounted and adjusted to normally maintain their bottom closing relation in the absence of material in the bin, a track secured on the outer side of the bin and interrupted throughout approximately the length of the dumping sections, a locking member carried by and movable with these sections, a slide coöperating with the track and set locking members to maintain said members and sections in relatively fixed positions with relation to the bin, and standards depending from the slide.

7. A coal delivery apparatus comprising a bin supported above the track, a plurality of dumping sections forming the bottom of the bin, each of said sections being pivotally mounted and adjusted to normally maintain their bottom closing relation in the absence of material in the bin, a track secured on the outer side of the bin and interrupted throughout approximately the length of the dumping sections, a locking member carried by and movable with these sections, a slide coöperating with the track, set locking members to maintain said members and sections in relatively fixed positions with relation to the bin, standards depending from the slide, and manually adjustable means carried by the car traveling beneath the bin to engage the standard and operate the slide.

In testimony whereof I affix my signature in presence of two witnesses.
